UNITED STATES PATENT OFFICE.

FRANK F. TAYLOR, OF NORWOOD, OHIO, ASSIGNOR TO THE FRANK F. TAYLOR COMPANY, OF NORWOOD, OHIO, A CORPORATION OF OHIO.

DESIGN FOR A CHILD'S VEHICLE.

Application filed July 18, 1927. Serial No. 22,790. Term of patent 14 years.

To all whom it may concern:

Be it known that I, FRANK F. TAYLOR, a citizen of the United States, residing at Norwood, in the county of Hamilton and State of Ohio, have invented a new, original, and ornamental Design for a Child's Vehicle, of which the following is a specification, reference being had to the accompanying drawing, forming part thereof.

In the drawing:

The figure is a perspective view of child's vehicle showing my new design.

I claim:

The ornamental design for a child's vehicle as shown.

FRANK F. TAYLOR.
